SOLE CEMENTER

Elzear J. Le Gault, Haverhill, Mass., assignor, by direct and mesne assignments, to Bestco Shoe Machinery Inc., Ipswich, Mass., a corporation of Massachusetts

Application October 4, 1937, Serial No. 167,117

4 Claims. (Cl. 91—51)

My invention relates to machines for applying cement to the margins of soles used in the manufacture of shoes by the so-called "cement process." Briefly speaking, the soles are treated by roughing the margins on the flesh side, applying pyroxalin or other liquid cement to the roughened portions or zones and then allowing the cemented soles to dry in racks. Subsequently, the cement is softened by a suitable solvent which evaporates after the sole has been applied to the shoe on a last with the result that the sole is permanently attached to the shoe bottom. The multitude of operations necessary in the manufacture of good shoes makes it highly important that each operation shall be as speedily conducted as possible to make the period between orders and shipments as short as is compatible with efficient work. The manufacturer who can turn out good shoes in a brief period after an order is received enjoys an important competitive advantage. This is especially true of women's shoes which change styles so rapidly that it is impossible to maintain continuous production based on future orders.

With this background in mind, I have constructed a machine by which cement may be applied to soles more rapidly than by known machines and which also performs its function in a thorough fashion.

The most important object of my invention is to provide a machine constructed and arranged to apply cement to soles more rapidly than has hitherto been possible. To this end I provide a cement-conveying feed roll rotating in a reservoir of cement and a presser roll over the feed roll. The presser roll is adjustable vertically as well as being so mounted that its axis of rotation can be varied to any desired angle to the horizontal. The presser roll is mounted in a bracket which is mounted for yielding movement up and down. An important feature of my invention is a flange on the inner end of the presser roll which acts to press the entire marginal surface of the sole against the feed roll. With this construction, a uniform coating of cement is applied to the margin of the sole.

These and other features and advantages of my invention will be best understood and appreciated from the following description of a preferred embodiment thereof selected for purposes of illustration and shown in the accompanying drawings in which—

Fig. 1 is a view in side elevation of a machine according to my invention,

Fig. 2 is an end view of the machine in perspective; and

Fig. 3 is a view in plan of a detail thereof.

The embodiment of my invention portrayed in the drawings comprises a machine having an elongated cement reservoir or tank 10 mounted on a pair of tubular standards and provided with an inclined bottom and a horizontal cover 11. The cover 11, which is normally screwed down, extends over approximately two-thirds of the top 10 of the reservoir 10, the remainder of the tank being covered by a thick flat plate 14 adapted to be swung upwardly about a pivot rod 13 journaled in upstanding apertured lugs 12 (one of which is not shown) integrally formed with the cover 11. The plate 14 acts as a supplementary cover for the reservoir 10 and is normally held in horizontal position by a screw 15 which extends downwardly into the end wall of the reservoir 10.

The supplementary cover 14 may be swung upwardly to expose the interior of the cement reservoir 10. A shaft 16 is disposed horizontally within the reservoir 10 and is driven by a pulley 17 secured on one of its ends; the pulley 17 may be belted to any suitable source of power. A downwardly extending lug 18 secured to the underside of the cover 11 is apertured to form one bearing for the horizontal shaft 16. A knurled, cement-carrying feed roll 19 secured to the outer end of the shaft 16 partially protrudes through an elongated rectangular aperture in the supplementary cover 14.

Referring now to Fig. 3, it will be seen that a horizontally disposed apertured slide 20 carried in the supplementary cover 14 embraces the roll 19 and may be moved longitudinally by manipulation of an adjusting screw 21 to vary the distance between the surface of the roll 19 and the interior front edge of the slide 20. The latter edge serves as a stripper, whereby the depth of the film of cement on the roll 19 is maintained constantly at predetermined thickness. In other words, the amount of cement to reach the sole is determined by adjusting the slide 20 back and forth. It is to be noted that the adjusting screw 21 is placed at the rear of the machine in order to avoid the interposition of elements between the operator and the machine. A vertical gauge roller 22 is adjustably secured on the supplementary cover 14 adjacent the crown of the roll 19 to aid the operator in regulating the width of the margin of the sole to be cemented.

To the supplementary cover 14 an angle bracket 25 is yieldingly secured by bolts 26 having helical compression springs embracing the lower 55

portion of their shanks. With this arrangement the bracket 25 may be displaced upwardly by pressure of the sole greater than that exerted by the springs in urging it downwardly. To the 5 vertical portion of the bracket 25 a vertical recessed slide 27 is secured by a horizontal clamping screw 28 working in a slot in the bracket 25. The recessed slide 27 has a horizontal portion through which a vertical adjusting screw 29 is 10 threaded with its lower end abutting against the top of the bracket 25. By manipulating adjusting nuts 30 and 31 on the screw 29, the vertical position of the slide 27 may be regulated. A block 32 is pivotally mounted at 33 within the 15 recess in the slide 27. A screw 34 holds the block 32 in position against the action of a compression spring embracing the shank of the screw 34, said spring tending always to rock the block outwardly at its upper end. A flanged presser roll 36 20 is rotatably mounted on the angle piece 32 by means of a stud 35 which acts as a journal, the presser roll 36 and the roll 19 having parallel axes in a vertical plane.

In operating the machine, the distance between 25 the rolls 19 and 36 is determined by manipulating the nuts 30 and 31 to move the slide 27 up or down and then the slide 27 is clamped in adjusted position. A sole is then pushed in between the rolls 19 and 36 so that the operator 30 may see how the roll 36 presses the sole against the roll 19. By turning the screw 34 the angle of the axis of the roll 36 is varied until the under surface of the sole is held flat across the roll 19. The inner flange of the roll 36 bears on the 35 inner margin of the sole to prevent it from tilting. When the sole is fed into the machine so that the feather edge of the shank is beneath the flange on the roll 36, the reduced edge is bent downwardly so that the bottom of the sole is presented flat across the feed roll 19, the outer edge of the roll 19 holding down the inner portion of the sole and preventing tilting. The 40 spring mounting of the bracket 25 makes it possible to run through soles which vary about an iron (1/4s") in thickness. Thus, the machine may be adjusted for a light woman's sole and need no changes unless the work varies so that much heavier soles are to be treated.

Having thus described my invention what I 45 claim as new and desire to secure by Letters Patent is:

1. A machine for cementing the margins of soles, which comprises a cement reservoir, a cement-carrying feed roll disposed partially with-

in said reservoir, and angle bracket, bolts securing the bracket to the top of the reservoir, springs about said bolts for yieldingly securing the bracket to the top of said reservoir, a vertically adjustable slide secured to said angle bracket, 5 a block pivotally mounted on said slide, a spring disposed between the block and the slide and tending to rock the upper end of said block outwardly from the slide, and a presser roll rotatably mounted on said block. 10

2. A machine for cementing the margins of soles, which comprises a reservoir, a knurled cement-carrying feed roll, an angle bracket disposed on said reservoir adjacent said feed roll, bolts securing the bracket to the reservoir, springs 15 about said bolts permitting yielding movement of said bracket to and from said feed roll, a presser roll disposed above said feed roll, a vertically adjustable slide connected to said bracket, a block carrying said presser roll and pivotally 20 secured to said slide, and a spring urging said block and presser roll away from said slide.

3. A machine for cementing the margins of soles, which comprises, a reservoir, a cement carrying feed roll, an angle bracket secured on said 25 reservoir adjacent said feed roll, a spring disposed beneath said bracket and providing a yielding mounting for said angle bracket, a block pivotally secured to said bracket, a presser roll carried by said block, and a spring disposed between the block and the bracket and tending to 30 force said block and presser roll down and away from said bracket, whereby a slight increase in the thickness of a sole passing between the feed roll and the presser roll will be compensated 35 for by yielding of the presser roll and block with respect to the bracket, and a major increase in the thickness of a sole will be also compensated for by movement of the bracket on its mounting.

4. A sole cementing machine comprising a 40 cement reservoir, a cement-carrying feed roll keyed on a shaft journaled in said reservoir, a hinged cover having an aperture for said feed roll, a bracket having an upstanding portion, bolts securing said bracket to the cover, a plurality of 45 springs disposed around the bolts to provide a yielding mount for said bracket, a vertically adjustable plate hinged at one end to the upstanding portion of said bracket, a compression spring disposed between the plate and the bracket and 50 tending to swing one end of said plate away from said bracket, and a presser roll rotatably mounted on said plate.

ELZEAR J. LE GAULT.
